METHOD OF MANUFACTURING ELECTRICAL
NETWORK CIRCUITSJohn Adolph Sargrove, Shepperton-on-Thames,
EnglandApplication August 16, 1944, Serial No. 549,770
In Great Britain August 30, 1943

5 Claims. (Cl. 29—155.5)

1

The invention relates to electrical apparatus and in particular to apparatus or instruments such as are used in connection with telegraphic, telephonic, television reception and transmission and the like, in which a circuit system has to be arranged consisting of interrelated components such as resistive, capacitative and inductive circuit elements as well as amplifier and reproducing means such as valves, cathode-ray tubes, loudspeakers, and the like.

The invention is also applicable to other electrical apparatus such as low current switch and instrument boards and the like.

The principal object of the invention is to provide an improved and more economical method of manufacture.

The normal method of manufacturing electrical apparatus such, for example, as a radio receiver—for which my invention is specially applicable—is to mount the various individually made component elements on a supporting base or chassis—as it is usually called—and then connect them up in their proper mechanical relation by means of conductor wires soldered to the terminals of the various components.

It has, however, been suggested to provide insulating panels with conductor paths by electro-deposition, the conductor paths leading to, and being connected to, sockets into which specially made components such as transformers, condensers, resistors and the like provided with contact pins could be plugged in.

This proposal has not to my knowledge ever been carried out in practice.

The present invention, which has already been carried out by me experimentally, differs from these prior proposals in that according to my invention not only are the conductor paths applied directly to the panel or chassis but components themselves of correct predetermined electrical values are applied to the panel or chassis and interrelated together with their conductor connections. It will, of course, be understood that such components as valves and loud speakers cannot be applied in this way but both the breadth and limitations of the method comprising the invention will be made clear hereinafter, when the practical application of the invention to the construction of a radio receiving instrument is fully described. The invention can, however, be broadly stated as consisting of a method of manufacturing electrical apparatus consisting of interrelated component elements connected in circuit according to which electrical components or parts thereof of predetermined electrical

2

values and the conducting paths connecting the components in circuit are applied to and form integral parts of an insulating supporting panel.

It is to be noted that the term "panel" used herein is not to be regarded as limiting to flat constructions as the invention can be applied to curved surfaces and in particular to the walls of cabinets containing parts of the apparatus as will hereafter appear.

10 Moreover, the term "insulating" is not to be taken as implying that the panel is wholly of insulating material as in some cases conductive material may be incorporated in the body of the panel.

15 In order that the invention may be readily understood and carried into practice reference is made to the accompanying diagrammatic drawings throughout which similar letters and numerals of reference are used for corresponding parts wherever occurring.

In these drawings:

Figure 1 is a fragmentary plan view of a part of a panel or chassis showing interrelated components and circuit elements or connections applied thereto in accordance with the general principles of the invention; and Figure 2 is a cross section thereof on the line X—X of Figure 1.

These two figures are solely for the purpose of a general description of the invention.

20 Figures 3 to 22 are for the purpose of explaining the manufacture of a complete two-valve radio receiver;

Figure 3 being a perspective view of one side of a panel moulded from insulating material upon which a two-valve all mains amplifier is to be built up in accordance with the invention;

Figure 4 is the same side of this panel after the grooves and indentations thereon have been filled with conducting material;

25 Figure 5 is the circuit diagram of the complete amplifier but so drawn that only those parts in existence at the stage of production represented by Figure 4 are shown in full lines. (The full thick lines showing the parts visible in Figure 4 whilst the full double thin lines show the parts on the invisible side in Figure 4. The dotted lines are parts not yet present);

Figure 6 shows the same side of this panel after resistors have been deposited, whilst

30 Figure 7 shows the other side of this panel at this stage of production;

Figure 8 is again the same circuit as Figure 5, but with many more parts shown in full lines, and represents the stage of production arrived at 55 in Figures 6 and 7;

Figure 9 is the same as Figure 7, except that the eyelets, sockets and the like have been applied;

Figure 10 is the same as Figures 7 and 9 but with parts which cannot be made by this process such as valves, loud speakers and electrolytic condensers plugged into place completing the amplifier;

Figure 11 is the circuit diagram (similar to Figures 5 and 8) of the complete amplifier shown in Figure 10;

Figures 12 and 13 are perspective views of both sides of another moulded panel adapted to become the regenerative tuned circuit and associated aerial feed circuit of a radio receiver when it is combined with the Figure 11 amplifier. (The panels shown in Figures 12 and 13 have reached the same stage of the method of production as shown in Fig. 4);

Figure 14 shows the circuit of the above two figures;

Figure 15 is a fragmentary view of the panel in Figure 13 but after the resistors have been deposited;

Figure 16 is the same panel with sockets, springs, variable condenser plates, assembly studs and the like inserted;

Figure 17 is the completed circuit of this panel shown in Figure 16;

Figure 18 shows a complete all mains (110 volt) broadcast receiver made in accordance with the invention by the continuation of the completed panels shown in Figure 10 and Figure 16;

Figure 19 is a view in perspective showing the interior of a moulded cabinet adapted to house the apparatus depicted in Figure 18 which has been processed in accordance with the inventions enabling the above broadcast receiver to function at various voltages up to 250 volts (it also shows part of the external mains connection attached thereto);

Figure 20A is a fragmentary view of the underside of the cabinet (Figure 19) showing a tapping link provided to cut out various parts of the series resistor deposited inside the cabinet and thus adapt the broadcast receiver to the desired mains supply voltage;

Figure 20B depicts a similar fragmentary bottom view of an alternative cabinet arranged to have a mains switch included, which can be operated from the front of the receiver (shown here on top);

Figure 20C is the inside fragmentary view of such a cabinet showing two deposited conductor circuits both of which are adapted to be switched on or off by the insertion of two metallic springs into lugs and a moulding insert;

Figures 20D, 20E and 20F show diagrammatically the action of such a switch in co-operation with the deposited conductors (shown black);

Figure 21 shows the circuit diagram of the electrical parts of such a cabinet made in accordance with the invention;

Figure 22 is the complete circuit of such a regional broadcast receiver made by the combinations of three basic parts, made in accordance with the invention shown in full black lines (the vertical dot-dash lines showing the jointing place) which, with the five parts (otherwise made) shown in dotted lines form the complete radio receiver (made up of the parts shown by Figures 11, 17 and 21);

Figure 23A shows in a plan view a method of designing part of a supersonic-heterodyne receiver, the circuit diagram of this fragment be-

ing shown in Figure 23B. Figure 23A also shows a method of reducing leakage between adjacent deposits;

Figure 23C is a cross section of the above, showing also one method of transconnecting the circuit portions on either side of a panel with each other;

Figure 24 shows some of the alternative methods also in cross section;

Figure 25 is a cross sectional view of an example of reversing the sequence of production operations from first metallising and then graphitizing to the opposite;

Figure 26 shows a method of increasing the inductance of the coil in Figure 23C by making the plastic moulded panel from a substance having a high permeability such as powdered iron core material; it also shows a manner in which the dielectric of a condenser from the same material can be improved;

Figure 27 shows an alternative to the previous one showing the powdered iron core material moulded into the normal panel, which has a keyed cavity preformed to take it (the interrelated metal deposits being applied in the normal manner into the communicating grooves);

Figure 28 shows another alternative to the separation of conducting and insulating parts of the panel, in this case the metal is deposited on to raised portions as in the block printing technique, the deep lying part remaining unmetallised;

Figure 29A is a plan view of a further fragment of such a receiver and shows a method of designing a capacity coupled band pass filter with associated parts diagrammatically shown in Figure 29B, all of which are interrelated.

Figure 30A shows a plan view of an inductively coupled band pass circuit and associated parts, the circuit diagram of which is shown in Figure 30B;

Figure 31 shows in a cross sectional view an alternative method of coupling two inductors made in accordance with the invention;

Figure 32 is a cross sectional view of inductive elements, so produced and arranged as to enable the inductances to be varied, within small limits;

Figure 33A shows an example of a short wave band spread oscillator in a fragmentary plan view, part of the circuit diagram of which is shown in Figure 33B, which is adapted to operate on many wave bands;

Figure 34A shows a perspective view of a moulding made in accordance with the invention, adapted to form the rotor member of a double variable condenser;

Figure 34B shows a cross section of same;

Figure 34C shows in cross section a similar moulding with powdered iron core material moulded into the cavities for varying the inductance of two coils;

Figure 35A shows a perspective view of a moulding adapted to be the rotor of a variable condenser;

Figure 35B is a cross section of same;

Figure 36 shows a cross section of a moulded disc, one side of which is adapted for increasing the inductance of a coil and the other side for reducing it;

Figure 37A shows in fragmentary perspective view a method of increasing the inductivity of deposited coils by the insertion of conventional shaped powdered iron cores;

Figure 37B is a cross section of same;

Figure 37C is the plan view of an improved shape of powdered iron core for this purpose;

Figure 38 is a fragmentary plan view of a method of providing intimate coupling between the inductors;

Figure 39 is a perspective illustration of a method of assembling several plates made in accordance with the invention and by interrelating them with valves, cathode ray tubes, transformers and the like providing an economical method of manufacturing devices, such as oscilloscopes and television receivers;

Figure 40A shows a perspective view of a method of plugging a sub-panel made in accordance with the invention into another part of an electrical apparatus which may or may not necessarily be produced by the same method;

Figure 40B is a plan view of such a sub-panel; and

Figure 40C is a diagrammatic circuit of same;

Figure 41 is a fragmentary plan view of an alternative method of making connections to a valve from a deposited conductor network avoiding the need of sockets;

Figure 42 is a fragmentary plan view of a method, particularly suited for use with an electron-multiplier tube of making a resistance network and the conductor and tube contact parts in a very simple interrelated manner. The resistance material in this case can be squeezed into prepared keyed grooves in the moulding process akin to that depicted in Figure 27 for powdered iron core material.

Referring first to Figures 1 and 2, the panel *a* of insulating material has upon both side surfaces indentations of different depths such as *b* which when partly filled with metal (shown black and indicated by the reference *m* in Fig. 2) form one pole, or plate, of a condenser; and grooves, such as *c* filled with metal forming a conducting path or connection which under orthodox methods of manufacture would be a wire soldered at both ends. The hole *d* for fixing this panel mechanically to some other part of the apparatus e. g. the cabinet is surrounded by a circular groove filled with metal *e* which is interrelated with grooves similarly filled with metal such as *e*², *e* and *e*³.

A typical interconnection from conductor paths *e*, *e*¹, *e*² and *e*³ on one side of the panel *a* to conductor paths on the other side such as *f*, is shown between metal deposit *e*² with metal deposit *f* located on the nether side of the panel, the interconnection being provided in this case by an eyelet *h* pressed and riveted into a suitable hole.

Other conductor paths on the other side of the panel are groove *i* connecting point *f* and some other element not shown and shallow indentation *g* which lies directly opposite the above referred to deeper indentation *b*.

The latter two metallised indentations (*g* and *b*) form a fixed condenser the dielectric of which is of the same moulded plastic substance as *a* and is preformed at the same time as the whole panel, a thin web *w* (Fig. 2) being produced in the mould.

The preceding shows a typical case of a fixed condenser formed in situ already for use, completely interconnected to the circuit network and requiring no prefabrication and manual assembling, wiring and soldering operations to connect it into the circuit.

At *j* a hole is shown with the well known key way. This serves to locate a thermionic valve into the surrounding valve pin contact sockets such as *k*. It will be seen that these valve pin contacts are eyeleted right into enlarged termina-

nation lobes at the ends of the deposited metal conducting paths. This is an operation easily mechanised and avoids the use of and consequent need for wiring up a separate valve holder.

5 Coil *l* is a high frequency choke coil the outside turn of which is directly interrelated with the conducting path *e*², *e*³. The inside end communicates by way of an eyelet connection with an enlarged lobe of conducting path *c* and *g* in the other side of the panel *a*.

In a similar form to the interrelated deposited metal configurations on the main body of panel *a*, associated metal deposits can be arranged on a movable circular panel inserted into a clearance hole such as the switch rotor disc *o*. In this case the deposit *n* forms a movable metallic link between the switch contacts such as *p* which can be arranged around *o* at any convenient position.

It will be seen that the stationary switch contact blades, such as *p* are eyeleted right into the enlarged termination lobes of the deposited metal conducting paths. This is another operation easily mechanised and avoids the laborious switch wiring operation and also circumvents the need for careful inspection after wiring which is normally required to avoid wrong connections.

To ensure better contact for the switch the link deposit *n* can be reproduced on both sides of the rotor disc *o* and the stator contacts such as *p* can also be duplicated on both sides.

Having shown, by way of example, a wide range of circuit components and conducting paths that can all be conveniently deposited of one kind of conducting material such as metal of high conductivity, e. g. copper, other circuit elements such as resistors can be produced in situ such as *r*¹ (shown with slant shading in both figures) by depositing, for instance, graphite on to the surface of panel *a* in the space between the metal deposits *e*⁴ and the enlarged lobe terminating deposited metal condenser plate *b* thereby connecting it up into the circuit simultaneously with the formation of the resistor.

This avoids the need for manually inserting a separately prefabricated resistor component.

The deposited resistor elements, such as *r*¹, *r*², *r*³, *r*⁴, etc. can all be simultaneously deposited either employing printing technique and using an ink consisting of a colloidal graphite suspension as for instance by using marks or stencils and spraying this suspension with the aid of a paint spraying pistol.

Provided the specific density and thickness of the resultant deposit of graphite or other resistive material is accurately controlled the various resistance values required can be obtained by merely varying the aspect shape of the resistor deposit. As an example, using a certain colloidal dispersion of graphite in a suitable slightly glutinous medium (such as gelatine) and deposited to a controlled thickness of say $\frac{1}{20}$ millimetre one obtains a specific coating resistivity of 25 ohms per square millimetre area when measured from one edge to the parallel edge opposite. This small area is capable of continuously dissipating one milliwatt of energy in the form of heat without rising above a safe working temperature. A wide range of resistor values can be obtained by simply varying the shape and size of the deposit. A few instances will serve to illustrate this. A deposit area one mm. wide and 100 mm. long will

give in the above case a resistor of 2500 ohms. This will be able safely to dissipate $\frac{1}{10}$ of a watt ($=100$ milliwatts). Again a deposit 10 mm. wide and 10 mm. long will have a value of 25 ohms and

dissipate $\frac{1}{8}$ watt; another deposit 0.2 mm. wide and 100 mm. long would have a value of 12,500 ohms at $\frac{1}{10}$ watt; whereas a deposit 25 mm. wide and 40 mm. long would be 40 ohms at one watt.

Similarly other ranges of values can be obtained with similar shapes by varying the controlled thickness of deposit (i. e. varying the spraying time) or by changing the density of the deposit (i. e. by varying the dispersion of graphite in the medium).

In large scale production several pistons can be used depositing various dispersions of graphite in sequence in each case a different stencil arrangement being employed so that the required sprayed deposit goes to the required place in the circuit.

In practice, one can easily obtain a range of values from 1 ohm to 10 megohms with three different dispersions. Wattages in the lower ohmic values can be up to 10 to 20 watts. This range of values is ample for radio receiver practice. It may be considered a disadvantage of this method that the higher wattage values of resistors occupy more surface space than is the case with the prefabricated solid stick-like resistors. This is not necessarily a disadvantage as the heating up and continuous heat dissipation of these resistors is much more uniform and the reliability, constancy and endurance of resistors made in accordance with the invention is very high. It should be noted that the larger wattage resistors are according to this invention conveniently sprayed onto the surfaces of the cabinet walls, spreading out the heat radiating elements.

It should be noted that in these proposals the contacts to the two ends of the resistors is obtained without a separate operation by depositing the resistor right into its intended place in the circuit so that it overlaps the previously, or subsequently, deposited metal conductor path deposit over a sufficient area to achieve good contact. It is preferable so to shape the larger wattage resistors that the graphite deposit is widened near the contacts so that the temperature gradient at the line of contact between hot graphite and cold metal is not too sudden.

To enable a very long and narrow resistor to occupy a relatively small surface area it can be conveniently deposited in a meander or zig-zag form. Such a resistor is shown at r^4 (Fig. 1).

It is further convenient, in order to allow for slight inaccuracies in the alignment of the stencils to make the terminations of the metal paths also with enlarged lobes. Such a termination is shown at q .

Whereas the inductor coil l shown in Figure 1 has only three turns and thus has only a very small inductance value coils of this construction can be made with many more turns of narrower surface width and closer spacing and also a total greater surface space area.

Obviously the maximum value of inductance that can thus be obtained has an upper limit which is lower than the conventional wire coils. Several methods of raising the maximum inductance value of coils made in accordance with the present proposals are shown in Figures 23 to 38 and will be more fully described hereafter. In general the kinds of inductances required for radio-frequency work of the order of approximately $\frac{1}{2}$ megacycle to 100 megacycles can be arrived at by this means. Further, with certain modification of the described process involving the deposition of metal by known photo-chemical means either directly onto the main panel or onto a film and affixing same, including photo-

graphically deposited interrelated conductor paths and condenser plates and the like, by a suitable adhesive, the connections being made between the film and the main panel where required by the circuit by means of eyelets or the like, greatly increased range of inductance values are obtainable.

There are certain limits to the values of condensers that can be formed in the manner shown in Figs. 1 and 2, and if larger capacitance values are required there can be obtained in accordance with these proposals as follows: The condenser can be produced in situ by depositing first two metallic contacts one of which is as large as a condenser plate. This is sprayed over with a lacquer of high dielectric coefficient, except the narrower metal contact and a narrow edge of the larger plate, both of which are masked. A further mask is now used having a large cut out and enabling metal to be sprayed through it so that it makes contact with the metal conductor of narrow dimensions. This forms the second plate of the condenser. Now again lacquer is sprayed on with the same stencil as was used for lacquer before. Then metal is again applied through the first metal spraying stencil; and so on until a stack is sprayed in which every alternate metal layer forms one pole of the condenser and vice versa. Of course three or more pole condensers can be similarly produced. Moreover, many condensers in many parts of the circuit can be similarly and simultaneously made in this multiplate form and also other interrelated parts or conductor paths can be sprayed on top of lacquer allowing for instance a conductor path in between lacquer layers to cross over other conductor paths on the main panel as in between other lacquer layers.

A further alternative proposal of producing such interrelated condensers of higher capacitance value is to make the whole main panel from a material of very high dielectric coefficient for instance by using a plastic filler of a substance with such a high dielectric constant, or by inserting a thin layer of such a substance with a roughened or etched surface into the mould so as to form the thin web w indicated in Fig. 2 when the plastic moulding is completed.

A further alternative is to make a sub-panel of a substance having a high dielectric constant on which part of the interrelated conductor paths and the high value condensers are deposited and this sub-panel is connected into the main circuit by eyelets and the like providing also the electrical connections between the circuits on the two panels. In general terms the upper limit of capacitance values that can be conveniently produced by these means lie in the region of 1000 micro-microfarads, using Bakelite panel material and up to 30,000 micro-microfarads (0.03 microfarad) with special materials such as suitable ceramic.

To obtain the greatest production economy the circuit design should preferably avoid the larger values of inductances and capacitances. (In many cases the required time constants of a part of a circuit can be obtained with smaller values of reactive components if the corresponding resistive component is increased.)

When larger reactive components are indispensable (such as electrolytic smoothing condensers) these can be prefabricated with plug shaped outlets and plugged into suitable sockets inserted into enlarged lobes of the interrelated deposited metal circuit on the main panel a .

Having explained the general principles of the invention reference is now made to Figs. 3-22 which illustrate the method of production of a complete A. C./D. C. all mains 2 valve broadcast radio receiver, the complete circuit of which is shown in Fig. 22.

Figure 3 is, as before indicated, an isometric perspective view of one side of a moulded plastic panel 1 of insulating material prior to deposition of any other materials. The arrow which appears on the narrow edge of the panel on this and several subsequent figures serves to show which side of the panel is viewed and should be imagined as permanently inscribed on the panel.

Figure 4 shows the same side (see arrow) of the panel at a later stage in the production process after the moulding has been metallised all over in accordance with the invention by spraying the metal on from a pistol and thereafter face grinding the whole surface down with an abrasive in any known manner e. g. by a surface grinder so that only metal deposited in the grooves, holes and indentations remains on the panel.

Figure 5 shows diagrammatically the circuit scheme which this panel will ultimately carry. It will be noted that this is the same electrically as the portion between the vertical dot-dash lines of completed receiver Fig. 22. However an unconventional mode of showing the circuit has been adopted in Fig. 5 (also in Fig. 8 and Fig. 14) to show the progress of the production sequence. In these three figures which all represent the identical circuit all those parts not yet present on the panel shown in the preceding figure are shown with very thin dotted lines. These circuit components and conductor paths on top, i. e. visible, in Figs. 3, 4 and 6 are shown with full black lines, whilst those on the nether side in these figures but on top in Fig. 7 are shown as white lines, i. e. are thin double contour lines. The arrows in Fig. 6 and Fig. 7 serve to indicate which way up the panel is shown on the various figures.

Deep indentations 2a, 3a, 4a and 5a in the moulded panel 1 in Figs. 3 and 4 are intended after metallisation to form the top plates of each of the condensers shown with the same number in the circuit diagram, Fig. 5. To distinguish these deep indentations from through holes the shadow cast by the walls of the indentations is shown on the webs of moulded plastic material at the bottoms of the indentations. These thin webs will form the dielectric of these condensers. The reference characters from 6 to 30 on Fig. 3 are shallower indentations and grooves which will later serve as interconnecting conducting paths and termination lobes for sockets or eyelets. Their exact function will become clear to those versed in the art by comparison of Figs. 3 and 4 with Fig. 5. The number 1 which occurs several times in Figs. 3, 4, 6 and 7 relates to a large indeterminately shaped interconnecting metal deposit and its purpose is to act similarly to a grounding bus-bar of the metal chassis of a conventional receiver. It can be conveniently applied so that it is in continuous and intimate contact through the large round hole in the middle of the panel with another large interconnecting metal deposit on the other side of the panel. This is also marked 1 on Fig. 7.

In most designs of a radio receiver it is good practice to make this element as all-embracing as possible and to be continuous with the grounded condenser plates as shown at 3a and 5a in Fig. 4, and at 4b in Figs. 5, 7 and 8.

The various groups of smaller holes will be described later. The full black and white lines in Figure 5 show how many separate assembly, fixing, wiring and soldering operations of the normal set making procedure have been eliminated by the simple and economical expedient of designing the panel moulding with recesses of the proper depth and configuration and comparatively more shallow grooves interconnecting the same, and by metallising this panel all over and grinding off the surplus metal from both sides so as to leave the metal only in the grooved and recessed places.

Before explaining the parts in detail it will be noted that one of the reasons for the use of both sides of the panel is to allow the conductor paths to cross over each other, where required by the circuit. Another reason is to facilitate the arrangement of the fixed condensers in the circuit.

Figs. 6 and 7 show the application of the resistor elements, the resistors being shown as shaded areas; in this instance one operation only is required for each side, the two sides being sprayed with a different graphite dispersion, the specific resistance of the graphite deposit on the side of the panel shown in Fig. 7 being approximately ten times higher than that shown in Fig. 6.

Viewing Fig. 8 and where necessary the preceding Figures, it will be seen that we have resistor 31 (Fig. 6) of graphite deposited in a meander or zig-zag form between the lobes of metal conductors 19 and 20 to act as the anode load for the first valve. Another meander form resistor 32 is inserted between conductors 20 and 23 to act as a smoothing filter resistance. A straight narrow resistor with enlarged ends 33 is deposited between conductors 6 and 17 to act as a high-frequency stopper to assist regeneration in the aerial circuit which will be connected to point 18 (see Fig. 22).

A straight resistor 34 is deposited between conductor lobes 8 and 29 to act as a cathode-grid biasing resistance for the second valve of the set.

A very small resistor 35 is deposited between the circular metal deposit 36, which will ultimately be the contact for holding one of the loud-speaker sockets 56 (see Figs. 9 and 10) and a similar circular metal deposit 37 which will ultimately be the contact holding the appropriate one of the valve socket eyelets 55. This resistor will act as an anti-parasitic oscillation anode stopper for the second valve. The very large resistor 38 is deposited between metal conductors 14 and 15, and acts as part of a heater-filament series resistance. This is a good example of a relatively large wattage resistor. Another large resistor 39 is deposited between metal conductors 11 and 14 and acts as the other part of the heater-filament series resistance.

It should be noted that the arrangement of splitting an electrical circuit component—in this case the heater-filament resistance—into several separate parts, either for the purpose of better utilisation of the available panel space or for any other purpose for instance spreading the heat radiating members to different regions of the panel or the cabinet is easily accomplished in accordance with this invention and furthermore this does not involve an increase in production costs. This constitutes a distinct advantage over more orthodox methods of production.

The resistor 40 deposited between metal conductors 10 and 11 serves to limit the charging surge current flowing out of the rectifier valve 75 when the receiver is first switched on, for this

11

purpose it has a comparatively large area and will stand very great overloads. Conductor 10 also communicates with metal deposited condenser plate 4a, Figs. 4, 5 and 6, which acts as a by-pass to grounding metal deposit 7 for parasitic high frequency oscillations generated by the rectifier valve.

The meander form resistor 41 in Fig. 7 on the nether or under side of the panel (and consequently shown as double thin lines in Fig. 8) is deposited between the lobe 42 of the condenser plate 3b and conductor path 20 (Fig. 7) which transcommunicates by way of a small hole with conductor path 20 on the nether side (Fig. 6). This acts as a feed resistance for the screen grid of the first valve via the lobe 43 of the condenser formed by deposited plates 3a (Fig. 6) and 3b (Fig. 7), the latter acting as a high-frequency by-pass condenser for the same electrode. A very thin and long resistor 44 is deposited between the lobe 45 of the main grounding conductor deposit 7 and lobe 46 of the nether plate 2b of the audio-frequency coupling condenser composed of metal deposits 2a (Fig. 6) and 2b (Fig. 7). It will be noted that in the circuit shown in Fig. 8, the condenser plate 2b is in intimate direct contact with condenser plate 3b, the latter serving to produce a high-frequency by-pass for the control grid of the second valve. This direct intimate contact in this case is achieved as shown in Fig. 7 by making 2b and 3b into one individual peculiarly shaped metal deposit being in juxtaposition to the two separate deposits 2a and 3a on the former side of the plate (Fig. 6).

This facility of making high-frequency by-pass condensers in such intimate contact with the main (base) ground return is an advantageous feature which is not normally accomplished at such production economy. The very thin resistor 41 (Fig. 7) is deposited between lobe 48 of condenser plate 2b; 3b (Fig. 7) and circular metal deposit 49, the latter being the contact for the control-grid socket of the second valve.

An interesting feature of this system of producing a circuit arrangement is the facility enjoyed by the designer in screening certain sensitive points from "picked up" hum or unwanted leakage currents and like interference factors. A good example is shown here at 50 (Fig. 7) where a metal deposit going right to the side of the panel and attached to the socket of the cathode pin of the second valve (a relatively hum-free electrode), is used to screen the grid coupling condenser 2b of this same valve—a point very sensitive to external hum—from the influence by leakage or external radiation of the adjacent heater-filament contact pin, which is a point having a very intense hum voltage. Similarly on the other side of the panel the other plate 2a of this same condenser and its lobe 6 is screened from the humming points by the peculiar configuration of the main grounding electrode 7. This part of 7 is marked 9 on Fig. 6 and also at the same time acts as the means of interconnecting the grounding parts of this panel with the grounding parts of the other panel (see Fig. 18).

The point 51 (Fig. 7) is connected by way of metal path 52 to point 53. Path 52 has a high hum voltage hence it is run round outside the grounding electrode 7, so that the latter screens it from acting upon sensitive points. Coming back to the resistor 44, which is the grid-leak of the second valve and hence also sensitive to hum, this is likewise arranged to be screened by non-humming deposits 7 and 3b (see Fig. 7). Metal

12

deposit 54 in Fig. 7 is an interconnecting path for cathode and suppressor grid and one heater pin of the first valve (see Fig. 8) as well as a grounding screen member shielding the hum-sensitive anode circuit of this same valve from humming point 51.

Considering Fig. 8 only we now see that except for items such as valves, electrolytic condensers and loud-speakers, we have made every component. Whilst this involved preparatory designing considerations, it requires only a few actual production questions which can be stated as follows:

1. Moulding the panel Fig. 3,
2. Metallising the same all over,
3. Grinding the surface of the panel to obtain the condition shown in Fig. 4,
4. Spraying one graphite mixture through spaces on the surface of the panel shown in Fig. 6,
5. Spraying another graphite mixture on the side of the panel shown in Fig. 7,

and fifteen electrical components all of individual character and electrical value and in their correct location and more than 35 conducting paths all in their correct location have connected these components in circuit.

We now require to provide for the prefabricated components to be plugged in. This is facilitated by inserting eyelets, sockets or the like as shown in Fig. 9. As these are in definitely pre-arranged positions automatic insertion of these small items and automatic eyeleting, riveting and the like becomes feasible.

Fig. 9 shows the same side of the panel as Fig. 35. At point 20 an eyelet is inserted through the panel to act as an interconnection from conductors on either side of the panel. At points marked 55 suitably shaped metal eyelet tags are inserted so that they radiate conveniently from which ever direction they happen to come into the valve pin socket holes arranged in a circle around key-way hole mentioned above to act in combination as the valve holders. All such tags are not numbered, though all are shown, and they are deliberately drawn in a slightly bent and irregular line to represent more clearly that they are springy parts attached on top of the moulding and not part of the latter. Sockets 56 for the two loud speaker connections are inserted into circular metal deposits 36 and 59 previously mentioned, shown in Figs. 6, 9 and 11. Specially shaped springy sockets 57 and 58, 60 and 61 are inserted into holes and cavities 21, 24, 30 and 42 formed in the panel, which have been previously provided in the metal deposit paths (see Fig. 3) to act as sockets for the positive terminal plugs of electrolytic plug-in condensers. The individual function of each of these items becomes clear by comparing Fig. 11 with Figs. 10, 9, 8, 7 and 6.

60 It is preferable to spray the panel shown in Fig. 9 with lacquer to protect the deposited circuit, the relevant electrical connections and sockets being, of course, masked during the lacquering operation. This panel is now ready to have 65 the prefabricated components plugged in as shown in Fig. 10. The valve marked 65 is the first valve previously mentioned and in this case is chosen to be of a type having its grid terminal 66 on top to facilitate its connection to the second panel to be described later, which carries the aerial input circuits.

The valve marked 67 is of the type containing an output system as well as a rectifier system. The loudspeaker 68 contains its own output transformer and in this example is of the perma-

net magnet moving coil type, it is affixed by quick fix screws or rivets to the main panel and the output transformer loads are directly plugged into the two previously mentioned sockets 56 without the aid of the usual individual soldering tags. This again avoids the usual soldering operation. Of course the output transformer leads are provided with suitable flexible lead ends of the type normally used in light current electrical apparatus. The combination spring and ground clip 69 shown best in Fig. 10 as mounted on connecting stud 70 (Fig. 10) is mounted right into the large main grounding metal deposit 7 at the hole 70a (Fig. 9). The connecting stud 70 acts as a support for the second panel and also being electrically conductive as a further ground return lead for the tuning circuit, on the second panel, which is shown in Figs. 12 and 13 and also as the negative return by way of the spring 69 from the body or case and negative terminals of the electrolytic condensers 71 and 72. The latter are designed to be identical containing a large and a small condenser each, the circuit being so designed and the clips 57, 58, 60 and 61 (Fig. 9) so laid out that it is impossible to plug these dissimilar twin condensers in the wrong way round; i. e. the larger condenser will always plug into that part of the circuit which requires the larger capacitance value. This combination becomes more clear when considering the complete circuit Fig. 22. In Fig. 11 the conventional method of showing the completed circuit all in full line, has been adopted, it being no longer necessary to differentiate between the top or bottom of the panel.

It will further be noted that this panel now comprises a 2-valve amplifier and rectifier unit ready for use on A. C. or D. C. mains. The only addition required of course is the input means of for instance a microphone and battery, the latter being arranged also to serve to bias the open grid 68 of the first valve.

One side of the second panel 80 is shown in Fig. 12, and the other side in Fig. 13. It is also, as before, a moulding with deep indentations or recesses and grooves filled in with metal, but in this case, in addition to condensers, conductors and resistors and terminations, it also contains inductances. These occur on both sides (Figs. 12 and 13) and are coupled to each other through the plastic material of the panel. For convenience of illustration and for greater clarity, the inductor coils are symbolically shown with only a very few spiral turns on each side, but of course in actual practice their number of turns would depend on the band of frequencies of the station for the reception of which the receiver has been intended. For medium wave broadcasting stations the coil on the face shown in Fig. 12 would have about 25 spiral turns and that shown in Fig. 13, about 7.

Fig. 14 shows the diagrammatic scheme drawn again according to the convention hereinbefore adopted. By comparing Figs. 12 and 13 with Fig. 14; the function of each part will become clear. Fig. 15 which shows the same side of this panel as Fig. 13 but after the graphite deposit has been applied, and Fig. 16 which shows the same side of this panel after metal sockets, pillars, clips and moving condenser vanes including insulation have been affixed, and Fig. 17 which shows the completed circuit of this panel. By reference to Fig. 18 and the left hand portion of Fig. 22, the manner in which this panel (Fig. 16) cooperates with the previously described two

valve amplifier to form a complete radio receiver, will become clear.

In Fig. 12 it is assumed that a moulded panel has been metallised and ground off on both sides leaving the metal deposits in those parts lying beneath the surface level. Two square deep recesses 81a are located in the area covered by a shallow indentation 82, which interconnects them and shallow groove 83 as well as oblong shallow indentation 84. These are all collectively metallised and are associated through two holes with a metallised shallow indentation also shown as 84 in Fig. 13. From Fig. 14 and Figs. 16, 17 and 22, it will be seen that this group of metal deposit is the condenser plate which will be ultimately associated with the input grid of the first valve by way of the spring contact 84s (Fig. 16). The circular surface area 85 (Fig. 12) in the midst of this metal deposit is left unmetallised and is an insulating area containing a screw-threaded hole for the screw shaft of the variable tuning condenser.

The other pole of the fixed condenser 81b is clearly seen on Fig. 13, but it will be seen from Fig. 14 that it is electrically intimately connected to the stationary plate 89b of the variable tuning condenser and hence in this actual design Fig. 13 one and the same metal deposit constitutes a plate for both condensers and, therefore, in the drawing is indicated by both characters 81b and 89b. From Fig. 14 it will also be seen that one of the poles of the aerial feed condenser 87b is electrically connected to the above condenser pole by metal path 88. The actual position of 88 is shown on Fig. 13 and the other pole of this condenser 87a (Fig. 14) appears also as 87a in Fig. 12. The aerial socket 86 (Fig. 14) for the insertion of a plug attached to a low capacity small indoor aerial, will ultimately become affixed according to the panel as shown in Fig. 16.

Fig. 14 also shows that the interrelated metallised deposit system consisting of condenser plates 81b, 89b and 87b and conductor path 88 is also connected to the main tuning inductance coil 91 on the other side of the panel. This is accomplished quite simply by providing a small hole 90 (Fig. 13) which communicates with the lobe 90a (Fig. 12) which is the inside end of the spiral metal deposit inductance coil 91 (Fig. 12). This same hole 90 will ultimately contain a contact eyelet (or quick fix screw or the like), to attach this condenser pole to any further spring leaf type condenser vanes it is necessary to attach to increase the capacity of the variable condenser 89b and 89s in known manner.

The inductance 91 (Fig. 14) in practice is a spiral coil 91 shown in Fig. 12 running from an inside termination lobe 90a to its outside termination lobe 92. This lobe by way of a hole is interrelated with another termination lobe on the other side of the panel shown in Fig. 13 and indicated as 92a. The small round hole in metallised termination lobe 92a will contain a fixing screw or the like connecting it by way of a conductive stud 92p (Fig. 16) with a metallised termination lobe 9 in Fig. 6 which is in the other previously described panel and acts as one of the ground return conductor paths. This is more clearly seen in Fig. 13. From termination lobe 92a (Fig. 13) a conductor path 93 runs and is widened out at its other end to form one of the stationary condenser poles 94b of the rotary differential condenser shown in Fig. 17 as 94. The other stationary pole of this differential con-

denser is 94c (Fig. 13). From Fig. 14 it will be seen that this is electrically connected to one pole of an aerial feed condenser 95b. In the embodiment shown in Fig. 13, 95b is an integral part of the metal deposit of the previously mentioned condenser plate 94c.

The other pole of this very small condenser is shown in Fig. 12 as 95a and is designed to be connected to a long large capacity aerial, such as a telephone line or the like as for wire borne 10 radio frequency currents. It is inductively coupled to the main tuning circuit consisting of coil 91 and condenser 89 (Fig. 17) through the smaller inductance coil 96. The actual interrelation between condenser 95 and coil 96 is clearly shown at 98 where a conductor path interconnects 94c (including 95b) with coil 96. The same metal deposit also continues on in metal paths 98 and 99 to associate with similar, but larger, aerial feed condenser plates 100b and 101b. Their other plates in juxtaposition are 100a and 101a respectively shown in Fig. 12. These condensers serve a similar purpose to condenser 95 (see Fig. 17) but are intended to match somewhat smaller capacity aerials or land lines. A noteworthy point in the design of condenser 100 is that this shows an example where the designer can utilise peculiar shaped condensers to fill in odd shaped spaces left on a panel by other constituent elements such as spiral coils and the like. The elongation of the deep indentation 100c (Fig. 13 and Fig. 15) would weaken the panel 89 and hence the cavity may be subdivided by a ridge under shallow indentation 100d (Fig. 13).

A further useful design feature is shown at the inside end 102 of the spiral metal deposit 95. This large deposit is not a condenser element but a large contact area to which a spring-like flexible variable condenser plate 89s (Fig. 16 and Fig. 14) is eyeleted to the two outer holes of 102, the middle hole serving for the insertion of a screw to hold the second ground return by way of the stud 70 (Fig. 10) previously mentioned.

In Fig. 13 a grounding pole 92a is on the edge of the panel whereas the inductive requirements of coil 96 are such that the inside spiral must be grounded and a conductive path cannot be grooved through either spiral coil on either side of the panel without destroying the inductance. Hence in this case the inside spiral turn is interconnected with point 92a by way of stud 70 and the metal deposits 7 and 9 on the other panel 1. It should be mentioned that when this is not practicable, resort can be had to a method described above in connection with general design of inductances, namely, to deposit across the previously deposited inductance a film of insulating material, such as lacquer in a manner such as not to cover the two points to be interconnected and through a stencil spray, or otherwise deposit, a connecting link which at its terminations makes metallic contact at the two points.

Fig. 15 is a fragment of the same plate 80 as Fig. 13 with the addition of the high value grid leak 103 across condenser 81 (Fig. 17) deposited in meanderform or other convenient shape so that at its ends it overlaps a lobe of metal deposit 81b and contact deposit 84. Fig. 15 also shows the addition of a separate plate of dielectric material, for instance mica 104 for the rotary condenser depicted as if it were transparent. It is preferably fixed with eyelets 105 and 106 to the panel 80. Of course under certain circumstances this can be also a sprayed-on hard dielectric film. Fig. 16 shows the same side of panel 80 as Figs.

13 and 15 but completed by the insertion of eyelet sockets 86, 86b, 86c, and 86d shown also diagrammatically in Fig. 17; valve input control grid contact spring 84s (also Fig. 17); the dielectric plate or plates 110 for springy expansion condenser plate 89s likewise eyeleted in; the rotary differential condenser member 94a which in this case is a diecasting including its shaft which protrudes through hole 111 (Fig. 15), and has on it a knob 112 and tensioning spring washer 113; the grounding studs 92p and 70 as well as the stud 109 supporting also a leaf spring 108 which presses upon a steel ball 107 to provide a smooth contact with the rotary condenser vane 94a. The latter stud 109 is more clearly seen in Fig. 18 where it will be seen as a stud interconnecting spring washer 113 (mentioned above) by way of conductor path 114 with panel 1 by way of fixing and contact hole 18 seen also in Fig. 6. This stud 109 brings the radio frequency currents which have been amplified by the first valve at point 17 (Fig. 22) to act by way of coil 96 in an inductively regenerative sense upon the tuned circuit consisting of coil 91 and the condenser 89 (Figs. 17 and 22). It should be noted that this regenerative sense is achieved in the design of the moulding tool which produces the plate 80. The mutual inductance having a predetermined sense, no human error can reverse this sense as so often occurs in the manufacture of coils. Fig. 18 also shows the main tuning condenser knob 115 which is attached to a screw 115a (Fig. 16) in threaded hole 85 (Fig. 12) and which when rotated several times compresses spring leaf 89s (Fig. 16) against mica 110 (Fig. 16) and metal deposit 81b (Fig. 15) increasing the variable tuning condenser 89. Both knobs 112 and 115 (Fig. 18) are in this case assumed to be screw driver operated semi-variable members. The third interconnecting stud 70 previously mentioned of the two plates 1 and 80 is not visible in Fig. 18 but its fixing screw 70a can be seen. The three studs connect the two plates rigidly in spaced parallel relation and provide a complete manufactured article in a functioning condition which can be affixed into any suitable shaped cabinet or built into some other apparatus. The points at which the A. C. or D. C. voltage mains can be applied to this piece of apparatus are shown as contact strip 11 in Fig. 6; and point 70a on Fig. 6 (the latter communicates with the entire deposit marked 1). An example of such a cabinet 79 is shown in Fig. 19 which is a broken perspective view in a position ready to receive the complete unit Fig. 18. (The arrow on the side of both Figs. 18 and 19 which has been used throughout will facilitate finding the parts which will interconnect when the complete unit of Fig. 18 is inserted into the cabinet.) Spring contact posts marked 70b and 11b in Fig. 19 register and connect with the corresponding points 70a and 11 on panel 1 (Figs. 6 and 7). (Also see points 11b and 70b in Fig. 22.)

A convenient method of adapting a piece of electrical apparatus to other than a predetermined operating voltage is illustrated here where, in accordance with the invention a series resistance and contact strips, tapping points and the like are all deposited in an interrelated manner onto the walls of the containing cabinet.

Fig. 20A shows a fragment of the outside of the bottom of such a cabinet 79. In Fig. 19 and Fig. 20A plug in sockets are shown, the corresponding ones bearing the same characters. In this case socket 122a in the centre (Fig. 20A) is electrically united with metal deposit strip on the

inside of the cabinet leading to point 122b to which one of the flexible mains leads 123 is attached. The link 124 in Fig. 20A is shown plugged into this control socket 122a and one of the tapping points 120b. In Fig. 19 tapping point 120b is electrically united with deposited metallic tapping spring 120a. In a similar manner socket 121b conducts to 121a; and 119b to 119a; and 116b to the terminal connection 116a associated with spring post 11b. Over these deposited conductor strips a wide graphite coating is deposited consisting in this case in a long length 125 on four sides of the cabinet and two shorter lengths 126 and 127. These are all shown on the complete circuit diagram Fig. 22 from which their function becomes clear. They are to extend the range of mains supply voltage of the apparatus in Fig. 18, designed for instance for 110 volts, to 210, 230 and 250 volts.

Fig. 20B depicts the bottom of a cabinet 128 produced by the proposed method in which a double pole switch 129a is incorporated. The toggle handle 129 is a moulded loose insert of insulated material more clearly seen in Fig. 20C.

The spring leaves 130s and 131s are supported in a slot 132 in the toggle 129 (more clearly seen in Fig. 20D) and in the recess in the moulded lug 133. The operation of such a simple switch can be seen from Figs. 20D and 20E and 20F. In position 20D the toggle handle 129 is at rest in its upward position and spring 130s (whose natural free shape is flat) presses firmly onto the ends of the two deposited metal contacts 130a and 130b. Fig. 20E shows the toggle in a downward motion and in an intermediate position. This first part of the movement causes only that part of the spring near itself to rise and the circuit through the spring leaf is still in being. When however the toggle handle has been moved right down the spring very suddenly jumps up into its other position of equilibrium as shown in Fig. 20F, causing a sudden separation from the contacts 130a and 130b and thus a sudden break of the circuit. This type of switch can be made to carry, in the arrangement shown, the kinds of currents met with in radio receiving apparatus and the like.

Fig. 21 shows the preferred circuit of such a cabinet with tapped deposited series resistor and double pole mains supply switch. This shows output contacts numbered 11b and 70b having the same significance as those shown in Fig. 19. All the other numbers have the same significance as those previously described in connection with Figs. 19 to 20F.

The purpose of Fig. 22 is to show the utility of the invention. It shows the complete circuit diagram of the one embodiment of the invention described in detail from Figs. 3 to 21. The part to the left of the dot-dash line 135 is the circuit arrangement contained on the panel 80 described above in connection with Figs. 12 to 17. This connects, by means of points 18, 84 and 9, with the circuit arrangement between lines 135 and 136, contained on panel 1, described in connection with Figs. 3 to 11, these combining to give the circuit of Fig. 18, which connect up via points 11b and 70b with the circuit contained in cabinet 128 (or 79) Figs. 19 to 21. From this it will be seen that an interrelated electrical circuit arrangement has been provided by a rapid and economical production procedure. In the example given herein the interrelated deposits avoid the need for assembling in the normal way some thirty individual component parts and the

making of over eighty soldered connections. In no case can the deposited circuit become incorrectly wired up as if the deposit is in existence at all it must be the correct circuit. By a method of design such as described, with the aid of a minimum number of prefabricated components such as valves, etc. which can obviously not be made by the method of the invention, in the case herein described five only of these components are required as shown by the dotted lines in Fig. 22, which can all be plugged in and thus a complete apparatus can be produced without the use of wire solder etc. and the attendant multitude of manual operations involved in the normal methods of manufacture.

It is obvious that this invention can also be applied to the production of more elaborate electrical apparatus than the example described in detail in the preceding pages and it is also clear that even if only part of such apparatus is made in this manner and other parts by more orthodox methods, the utility and economy achieved by it is substantial. The degree to which the designer will choose to make use of this invention will be governed by the magnitude of the production programme and is mainly one of economics. Generally speaking, the larger the production programme the more it will pay to include in the product design features which are in accordance with the invention. In the case, for instance, where several models of a certain electrical or radio instrument are made, having certain parts identical, it will be good economy to make that identical part of the instrument in this manner and incorporate it in the complete apparatus as if it were a composite component or sub-assembly. Such sub-assembly panels or groups of panels can be plugged or wired into the whole apparatus in the normal way.

Certain features arising from the invention will now be described, by way of example, as guidance to designers.

Fig. 23A illustrates a plan view of a fragment of the panel 140, upon which an interrelated circuit network is provided as shown diagrammatically in Fig. 23B. This may be the demodulator circuit of a constant frequency amplifier, such as the end member of the intermediate frequency amplifier in a supersonic heterodyne receiver. Fig. 23C is a cross sectional view through the line y—y shown viewed in the direction of the arrow shown in Fig. 23A. This shows an inductance coil 141 in which a spiral deposit is provided on both sides 141a and 141b of the panel (Fig. 23C); interconnection between the inside spiral turn of each in this case is provided by the eyelet 142 (which sits in a hole each end of which has a shallow depression the same depth as the spiral groove, the latter filled with metal at the same time as the spiral grooves). The semi-variable condenser 143 (Fig. 23B) for tuning this circuit to the exact fixed frequency required has its two plates 143a and 143b, Figs. 23A and 23C directly interrelated with the two outside spirals of the inductance. Eyeleted into the deposit 143a (with the same eyelets 144 and 145 holding the valve sockets of the grounding contacts of the self-contained valve holder) is the variable grounding incremental plate of condenser 143 consisting of spring plate 143s (Figs. 23A and 23C). This is positioned with reference to a lug shaped deposit 143c in the underside cavity of the plate 140 in known manner by screw 146. It will be noted that the dielectric of this condenser 143 consists partly of the web of insu-

lating moulded panel substance, made as thin as possible, see 140W, Fig. 23C, and partly of air. As the stationary deposited condenser plate 143b requires to be electrically connected to one pole of the fixed condenser 147 (Fig. 23B) it is convenient to make this in one with the previously mentioned plate 143b; hence the latter is simply enlarged as shown in Fig. 23A at 147b. From the circuit Fig. 23B the other plate of condenser 147 requires to be connected to the diode of the valve and to have a high resistance leak to the grounding pole of the system.

The simple manner in which this is accomplished is shown in Fig. 23A at 147a metal being deposited, and associated by lobe 148 (Fig. 23A) with the diode anode pin socket of the valve (Fig. 23B) and by another deposited lobe with resistance 149 deposited to overlap this and a similar lobe on the previously mentioned condenser deposit 143a.

To reduce electrical interaction from surface or dielectric leakage of mechanically adjacent parts deposited onto a panel but which electrically belong to different parts of the circuit the moulded panel is provided with a thin space 150 in Fig. 23A like a saw cut slot between such parts. This can have any suitable shape. In the metalling operation this should be masked so that the slot remains empty. It is sometimes advantageous to fill such a slot with metal and allow it to be associated with a grounding part of the circuit and thus provide a screen. One can also have two slots, one of each kind.

Fig. 23C shows a method of transconnection (of circuit parts on one side of the panel with circuit parts on the other) by means of an eyelet 142. The previous descriptions of embodiment have all shown this method but without departing from the invention many other methods of transconnection are possible.

Fig. 24 shows in cross section several such methods. In this figure a shows transconnection of the metal deposits on either side of the panel (shown black) by a thin rivet. This can be conveniently inserted by a special machine which pierces a hole, then inserts the end of a wire carried as a coil on the machine, then cuts off the required length, and finally squeezes it forming the two rivet heads. This involves piercing a hole after the metal deposit has been made. An alternative is shown at b where the thin hole is provided in the moulding by a tapered needle in the moulding tool at the bottom of a groove which will later contain the metal deposit. A short length of wire is forced into this tapered hole and is either riveted over or even left as it is, whereupon the metal which is deposited into the grooves on either side becomes intimately transconnected. This is a method particularly advantageous when making tapping points to inductance coils.

At c is shown a variant of a where instead of riveting the wire is clinched or bent over top and bottom. d is again a variant of c where the clinching is done before the metal deposit. If the apparatus is likely to be used in an atmosphere that is likely to contaminate purely pressure contacts, the transconnections can be made to cohere by the use of solder or the like.

The fact that the whole electrical circuit arrangement on one side of the panel is in a two dimensional plane permits the simultaneous soldering of all points at once. For instance, one can print with a suitably shaped rubber stamp and pad right onto all parts requiring solder a

colloidal suspension of tin, preferably containing a flux in the suspending medium, or a suitable soldering alloy and then heat up the whole plate when all points will simultaneously cohere to the associated metal deposits.

e and f show two methods of completely avoiding the need for transconnection of the metal deposits shown in black by a separate operation with a separate metallic part. The moulded panel itself, shown in cross section with the slant hatching, has a suitably shaped round hole or narrow oblong slot moulded into it and when the molten metal is sprayed on to both sides of the plate sufficient metal will penetrate to cohere with that on the other side to provide a transconnection conductor. At f is shown the hole as funnel shaped on both sides to make sure that the actual contact is not positioned in a random manner but in a fixed place. (This is especially useful for short wave inductances where the length of an inductance must be exact to quite small limits.) Fig. 25 shows a cross sectional view of an example where the sequence of operation hitherto mentioned, i. e. first metallising and then depositing the resistive material, is reversed.

In this case, which is particularly useful in connection with the deposition of complicated resistive networks (such as occur in oscilloscopes and television apparatus) the graphite shown with vertical shading 151 is first deposited onto the panel and can be applied into moulded smooth depressions 151d. (It is to be noted that it is known that graphite resistors will deposit more evenly and hence more uniformly if applied to a shiny surface and hence this method avoids the preliminary lacquering operation.) The metal layer 152 is in these cases conveniently printed on in conductive paint as the lower conductivity of metallic paint compared with a metal sprayed deposit is in this case completely negligible as the resistance material usually consists of members having values of the order of megohms. This method of inverting the deposition sequence is also useful when depositing a resistive network containing fixed as well as variable resistors or potentiometers 153 and 154 (operated by knobs such as k), such as the portion of the circuit shown on the rearmost panel 155 (in Fig. 39) of an arrangement which illustrates an oscilloscope or television receiver embodying this invention. The sliding contact (or wiper arm) 156 (Fig. 39) is of the usual construction in these cases and slides with light pressure on the deposited resistor material. A transconnection is shown symbolically at 157 in Fig. 25. Fig. 26 shows a method of increasing the inductance of a given shaped (e. g. grooved spiral system) inductor such as occurs in the device depicted above in Fig. 23A and Fig. 23C. In this case the whole panel is made of a moulded plastic material in which the filler contains a high proportion of molecular iron dust or other material imparting a high permeability to the substance, shown as an area filled with dots and marked Fe in Figs. 26 and 27. It will be noted that due to the separation of the iron molecules by an insulating film in the solidified moulding such a panel is non-conductive in the normal sense. However it is difficult to make a very thin film to act as the web or diaphragm of a fixed condenser and hence in this case the fixed condensers are either deposited entirely on one surface with sprayed lacquer dielectric and stencil sprayed second condenser plate as described above, or as depicted in Fig. 26 the web w is strengthened by

being sprayed with a thin coat of lacquer; this also acts as the main dielectric as in this case the powdered iron dust in the actual web acts as an extension of the other condenser plate. It is in this sense that the molecular iron acts as a conductor as before mentioned.

In Fig. 26 this lacquer layer is shown white on both sides of the web and marked "I." The metallisation marked black as before is deposited as before into depressions, or printed onto the plain surface. In view of the fact that the presence of molecular iron in some parts of the circuits is unwanted and even a disadvantage and is also much more expensive than other filler, it is better to mould the main panel of a plastic substance, and squeeze into a previously prepared cavity 158 (shown in Fig. 27) a limited amount of plastic with molecular iron dust filler. In this case it is advantageous only to partly cure the main panel before this other material is squeezed in and then completely cure with the spiral coil grooves and depressions simultaneously moulded across the boundary between normal filler and iron filler. Furthermore it is preferable to use the same basic plastic substance for both parts so that the whole mass coheres to form a solid body.

It should be mentioned that in the same manner as part of the panel can be moulded with a filler, or plasticize, containing different electromagnetic properties (as indicated in Fig. 27), it can also have a part containing a substance having different electro-static properties such as specially high dielectric properties, e. g. a ceramic product such as that known on the market as "Condensa." Part can also be moulded with a filler containing a high resistance material, such as carbon or silicon or a filler containing some other desired electro-physical property, the main feature of such combination of base materials being that in accordance with the invention the circuit deposits on the surfaces of the panel or the like are provided in an interrelated manner achieving the production economy above mentioned.

It may sometimes be an advantage to deposit the metal conductors not in grooves, or just on the plain surface, but actually on protuberances or ridges. This may be the case, for instance, where the apparatus has to work in humid atmospheres and where an arrangement in grooves or on a flat surface may produce surface leakage troubles. Also in transmitting equipment the higher power employed may make it desirable to carry the conductors on ridges. In this case the metal can be deposited on the ridges, see Fig. 28, 160 and protuberances 161, for instance by using the specially prepared moulding as if it were a printer's line block and contacting it with a pad saturated in conductive ink (e. g. colloidal graphite), allowing this to dry and then electro-plating it with metal. The resistors can next be applied by printing technique into the lower lying spaces provided therefor. This Fig. 28 also shows a feature of arranging the condenser blade inside the cavity in the form of an eyeleted plate. This feature is useful, for instance, if it is required to have several condenser plates adjacent to each other inside a deep depression and it would not be easy to keep these separate if the spraying method were employed.

The type of arrangement shown in Fig. 28 is also useful if it is desired to make the whole panel of a heat resisting substance, for instance, a ceramic material such as is known on the market as "Frequentite." In this case the metal deposit

constituting the interrelated circuit network consisting of resistive, capacitative and inductive components or parts of components can be produced on the ridges as described above by using the ceramic plate as the printing block but with an ink consisting of a suitable compound of silver, such as is used in pottery work for decorative purposes, which will decompose into metallic silver.

As further examples of useful design features, Fig. 29A shows a plan view of a fragment of a panel 163 carrying a capacitatively coupled fixed frequency band pass filter diagrammatically depicted in Fig. 29B. Obviously this can be made semi-variable as per Fig. 23A if more accurate resonance is required than can be provided by the tooled up moulded depressions. The two inductances 164 and 165 consisting of double sided spirals, transconnected with eyelets 142, are directly interrelated with condenser systems, whereby plate 166a and 167a is one deposit and serves at the same time as a plate of the resonating condenser 166 and also as a plate of the coupling condenser 167. The other pole of the resonating condenser 166 is shown as a dotted oblong marked 166b. The metal deposit representing the other pole 167b of the coupling condenser 167, shown as a dotted oblong, is also enlarged and acts at the same time also as the bottom plate 168b of the second resonating condenser 168 and also its lower elongation acts as one pole 169b of a further coupling condenser 169, the other pole of which 169a is again on top and is shown in full lines. The resistive component 170 is deposited quite simply across any suitable place where a lobe 171 is arranged.

Fig. 30A and Fig. 30B show a similar embodiment and taken together are easily understood from previous explanations. They represent an example of a partly inductively coupled band-pass-filter, the same numerals being used in these figures as in Fig. 29A and Fig. 29B where possible. However, in this case, by allowing the coils to overlap as indicated at M, mutual inductance of a definite predetermined amount is provided as also is a capacitative coupling of small magnitude marked dotted in Fig. 30B as 167. By arranging in the design the direction of the spiral turns it is possible to predetermine whether this predetermined capacitative coupling will aid, or detract from, the inductive coupling. It will thus be of value in determining the resultant band-pass characteristic which will be maintained in production, it being quite independent of human agency and thus not subject to human error, which is a trouble frequently experienced in normal coil winding.

Fig. 31 shows a fragmentary cross sectional view of another alternative method of coupling two deposited interrelated circuit networks, only the inductive elements 164 and 165 of which are shown here. 142 represents the usual transconnecting eyelet or the like whilst p is a pillar which can be made to an accurate length which when eyeleted into place by large eyelet 172 will predetermine the exact degree of coupling. This pillar can be a right and left hand screwed nut or the like which can make the coupling adjustable by varying the distance between the plates.

Fig. 32 shows another alternative where a powdered iron screw core 173 is used for varying the inductances and the coupling. In this figure the transconnection 157 is shown as made by the method described in Fig. 24B. If the apparatus requires parts of the circuit to be changed for

different purposes, this can be accomplished in accordance with the invention in many ways which only differ from each other in the particular method employed. This will be understood from one example described in connection with Fig. 33A which shows a plan view of a fragment of a panel carrying the circuit of an oscillator valve and having means for switching it to eight distinct wave bands by hand operation. The basic circuit which is that of a "Colpitt's" oscillator, is shown diagrammatically in Fig. 33B. The fragment of the main panel 175 is presumed to carry the main circuit of the apparatus whose band of operating frequencies it is desired to alter in distinct steps. This main panel contains a large clearance hole 176 in which a disc panel 177 is arranged to rotate freely, it being carried on an operating shaft (not shown) mounted through hole 178 and suitable bearings (also not shown). The free rotation of this disc is restricted by spring 179 which locks into notches as shown at 180. A fragment of only about a half of this disc 177 is shown but the whole disc would contain in this case four double spiral inductances marked 141 transconnected at their inside end by eyelets 142, as previously explained in relation to Fig. 23A. Their outside ends are directly interrelated with long arc shaped contact deposits shown as 181a on top and 181g on the bottom, shown dotted. It will be noticed that these deposits are slightly staggered, the reason for which will be made clear hereafter. At the sides of each coil are situated the associated preadjustable "trimmer" condensers 182, one pole of each of which is wholly deposited and the other is, in this case, a stamped out sheet metal segment. In the case of the "trimmer" condenser actually engaged, this metal segment is shown as 182s and is adjustable by rotation by the aid of a screwdriver inserted into the screw head shown at 182h. Electrical contact to this metal segment is made by the metal deposit 183a which terminates at the edge of the disc in the form of a short arc shaped deposit. The stationary plate of this trimmer condenser 182s is shown dotted and is a deep indentation on the other side of the panel, similar to plate 143c of Fig. 23C. The metal deposit inside this cavity is interrelated by way of a shallow groove with short arc-like shallow deposit 183g at the edge of the disc and acting as a switch contact. Contact arcs 181a and 183a make, in conjunction with the completely visible eyeleted lug, wiper type contacts indicated at a and aa respectively; whilst contact arcs 181g and 183g shown dotted make with the slightly visible eyeleted lug, wiper type contacts indicated at g and gg respectively. From Fig. 33B it will be seen that contacts a and aa go to the anode shown as A of the valve V, whilst contacts g and gg go to the grid of the valve marked G by way of an isolating condenser 184. The latter is a fixed condenser as previously described consisting of purely metal deposited plates 184g and 184b. The grid leak 185 is constituted by deposited resistive material as previously explained deposited across metal deposit c, eyeleted socket connected to the cathode pin of the valve and metal deposit G and eyeleted socket connected to the grid pin of the valve. The fine adjustment to the various wavelengths within the band, i. e. so-called "band spreading" is accomplished by rotating the variable double condenser of the "Colpitt's" oscillator 186. This can be stamped sheet metal or die cast disc with peculiar shaped openings z and z or can be a ceramic

dish shaped member as used in present-day trimmer condensers with an interrelated double metal deposit whose preferred peculiar shape is shown at s and s as will be more fully explained hereafter. This simultaneously alters the anode to cathode as well as the grid to cathode capacitance of the circuit by affecting metal deposited condenser plate 187 and 184g through a film of dielectric sprayed onto the top visible surface of the main panel 175. When it is desired to change the wave band by a distinct step to a slightly different one the disc 177 is rotated by shaft 178 to the next position or "click," say in a clockwise direction. The long arc shaped coil contact 181a which in the drawing makes contact with wiper contact a will not "make" with wiper contact aa, which will have lost contact with the condenser 182 which will have moved away in a clockwise direction, whilst the wiper contact a will engage the short arc contact 183x of another "trimmer" condenser. The same procedure will have taken place with the contacts g and gg. Moving two notches or clicks will change the coil also and cause a greater increase in wave band. The important and novel feature which emerges from a consideration of Fig. 33A is that by the employment of the invention it has been possible to make by simple means a highly complex electrical circuit which when made by normal wiring up methods requires a great deal of human care and vigilance and involves the use of many prefabricated components. Of course more such discs, such as 177, can be coupled together in various main panels spaced apart in a manner shown in Fig. 39, where the panels 192, 193 and 195 are interposed between the back panel 155 and the front of the cathode ray tube CRT in the panel 191. This renders possible the changing of several circuits simultaneously. Screening plates to reduce electro-magnetic coupling between adjacent discs containing coils such as 177 shown in Fig. 33A can be deposited onto intermediate plates, 192 (Fig. 39) which may contain other parts of the circuit such as deposited components associated with other valves 194. Some of these panels can be larger or smaller, a small plate being shown at 195, Fig. 39. This gives a wide range of possible combinations; moreover some panels, such as are shown in Figs. 40B and 40C carrying parts which may require to be at angles, e. g. "Magic-Eye" tuning indicator valve marked 196 in Fig. 40A can be arranged to plug into each other by plugs such as 197g, 197h, 197s, 202 and 207 in Fig. 40B and sockets eyeleted into metallised deposited lobes as before described, whereby the circuit arrangement on one panel such as 198 (Fig. 40A) becomes interrelated with the circuit on another panel 199 (Fig. 40A).

A more permanent interconnection can also be easily accomplished and nevertheless maintain detachability of the sub-panel by using screwed lugs 200 (Fig. 40B) secured by nuts.

The relevant parts of Fig. 40B and Fig. 40C are annotated in a manner clearly explaining the import and are substantially the same as similar circuit elements described above.

Coming back to matters of detail, Fig. 34A shows an alternative method of making a moulding for the rotor of the variable double condenser 186 shown in Fig. 33A. A cross section through the dot-dash line in Fig. 34A is shown at 34B clearly showing in black and marked m, the metal deposit also showing the upper surface of this metal rough as it comes from the spray gun. It is a point of the proposals that the accuracy of

the metal deposited electrical elements is determined by the shape and accuracy of the moulding or masking tools (in this case the mould) and not by thickness of the metal deposits which can be rough on the outside. The active part of this metal deposit *m* in Fig. 34B is its surface in intimate contact with the dielectric web *w*. This surface of the metal deposit is exactly the same on each moulding and is a function of the surface finish of the moulding tool. Figs. 35A and 35B 10 are similar mouldings but for a single or differential condenser such as used in the showing of Fig. 15 at 94a, and could be an alternative to the die casting shown in Fig. 15. This would obviate the mica plate shown in Figs. 15 and 14 15 as 104.

Fig. 34C shows a similar moulding to Fig. 34A but in this case the cavities are filled with molecular iron core filled plastic Fe as detailed above and serves the purpose of varying inductances in 20 known manner.

Fig. 36 shows an interrelated combination of embodiment 34C and 35B in both cases of which the accuracy of the product is determined by the moulding tools.

Fig. 37A is a perspective view of a fragment of a panel 216, a cross sectional view of the same panel being shown in Fig. 37B. This panel has upon it a deposited inductance 217 as described in the foregoing, shown also as a double layer coil in the cross section. In order to increase the inductance value of the coil, two powdered iron cores 218 of conventional design are inserted through apertures 219 in the panel suitably shaped to admit same. The two powdered iron cores 218 form a closed magnetic path of known characteristics increasing the inductance value by the difference in permeability value of this core material to that of air.

Fig. 37C shows the plan view of an improved core shape 220 to take the place of 218 in Fig. 37B. The part 220 has the same cross section as 218 but has four or more depending lugs 221, the shape of which is shown in Fig. 37B, the purpose of which is to increase the screening effect of the powdered iron core around the coil.

Fig. 38 shows a plan view of double spiral deposited coils consisting of two electrically separate spirals 222 and 223 on a fragment of a panel 224. This device permits very intimate inductive coupling between two circuits. Of course such a coil deposit can be fitted with powdered iron cores in accordance with Fig. 37A, B and C.

Lastly Figs. 41 and 42 show the most economical methods of making a valve holder as part of an interrelated circuit network in accordance with these proposals. Fig. 41 is a fragment of a panel 210 in which slots 211 are moulded. Metal deposit paths 212 are made to these as described above, the molten metal being allowed to flow into the slots as described in connection with Fig. 24e and f. Such an arrangement would be useful where only a very short functional life is expected of a valve and its circuit as, for instance, in apparatus used in meteorological balloons (which do not return) or special electronically controlled rockets, shells and the like. The method of deposition of the coating shown in Fig. 42 has been described in connection with Fig. 25 and is an example of a holder for an electron multiplier where the usual potential dropper resistances from electrode to electrode are not independent elements but are all deposited together as a ring 213 of a high resistance material upon which the metal contacts 214 are superimposed and at the

same time other conductor paths, e. g. 215 lead to other parts of the apparatus.

This is another case where the resistive material can be incorporated in the moulding process as the filler of the plastic material which is squeezed into position in the mould.

It will be seen from the foregoing that I have by my invention provided means whereby electrical circuits and their interrelated components can be constructed in a practical manner as integral parts of a panel or support and a number of panels or supports carrying circuits or parts of circuits of a complete apparatus can be mechanically and electrically connected together to form a complete apparatus—such as a radio receiver or transmitter—when essential plug-in components have been applied, which apparatus can be introduced into a containing case or cabinet in such a way as to ensure that electrical connection is established to the source of operating current.

What I claim and desire to secure by Letters Patent is:

1. A method of manufacturing an electrical network consisting of interrelated components such as inductances, condensers and interconnecting conductors, which method comprises the steps of forming on opposite sides of a rigid insulating panel spaced recesses each configured in accordance with the electrical character of the component to be made therein and with one recess on one side at least partially overlapping and of the same configuration as a recess on the other side, spraying conductive material onto both sides of said panel to coat said recesses as well as the adjacent face portions of said panel, and removing the coating from said face portions to thereby establish a circuit upon each side of said panel with said correspondingly configured and overlapping components on opposite sides electrically coupled through the insulating material therebetween.

2. A method of manufacturing an electrical network consisting of interrelated components such as inductances, condensers and interconnecting conductors, which method comprises the steps of forming on opposite sides of each of two rigid insulating panels spaced recesses each configured in accordance with the electrical character of the component to be made therein and with one recess on one side of each panel at least partially overlapping and of the same configuration as a recess on the opposite side thereof, spraying conductive material onto both sides of both panels to coat said recesses as well as the adjacent face portions of said panels, removing the coating from said face portions to thereby establish a circuit upon each side of each panel with said correspondingly configured and overlapping components on opposite sides of each panel electrically coupled through the insulating material therebetween, and assembling said panels by connecting electrically conductive studs between the panels to support the same in spaced relation, opposite ends of said studs being arranged in contact with conductive material on each panel to thereby interconnect the respective circuits on said panels.

3. A method of manufacturing an electrical network consisting of interrelated components including a condenser and interconnecting conductors, which method comprises the steps of forming on opposite sides of a rigid insulating panel spaced recesses each configured in accordance with the electrical character of the com-

ponent to be made therein, two of said recesses in opposite sides of said panel being transversely aligned to provide a condenser the dielectric of which is constituted by the web of insulating material therebetween, spraying conductive material onto both sides of said panel to coat said recesses as well as the adjacent face portions of said panel, and removing the coating from said face portions to thereby establish a circuit upon each side of said panel and which circuits are electrically related through the condenser coupling provided by the coatings on said aligned recesses.

4. A method of manufacturing an electrical network consisting of interrelated components including a pair of coupled inductances and interconnecting conductors, which method comprises the steps of forming on opposite sides of a rigid insulating panel spaced recesses each configured in accordance with the electrical character of the component to be made, two of said recesses being of spiral configuration arranged in at least partially overlapping relation on opposite sides of said panel to form the inductances, spraying conductive material onto both sides of said panel to coat said recesses as well as the adjacent face portions of said panel, and removing the coating from said face portions to thereby establish a circuit upon each side of said panel with the respective inductances electrically coupled through the insulating material therebetween.

5. A method of manufacturing an electrical network consisting of interrelated components including a pair of coupled inductances, a condenser and interconnecting conductors, which method comprises the steps of forming on opposite sides of a rigid insulating panel spaced recesses each configured in accordance with the electrical character of the component to be made, two of said recesses being of spiral configuration arranged in at least partially overlapping relation on opposite sides of said panel to form the coupled inductances, and two more of said recesses in opposite sides of said panel being transversely aligned to provide a condenser the dielectric of which is constituted by the web of insulating material therebetween, spraying conductive material onto both sides of said panel to coat said recesses as well as the adjacent face portions of said panel, and removing the coating from said

5 face portions to thereby establish a circuit upon each side of said panel and which circuits are electrically related through the coupled condenser and inductance components of each circuit.
